United States Patent Office.

WILLIAM H. ROSSER AND JAMES STIVER, OF MILL HALL, PENNSYLVANIA.

Letters Patent No. 99,352, dated February 1, 1870.

IMPROVEMENT IN FEED-CUTTER.

The Schedule referred to in these Letters Patent and making part of the same.

To all whom it may concern:

Be it known that we, WILLIAM H. ROSSER and JAMES STIVER, of Mill Hall, in the county of Clinton, and State of Pennsylvania, have invented a new and useful Improvement in Feed-Cutters; and we do hereby declare that the following is a full, clear, and exact description thereof, which will enable others skilled in the art to make and use the same, reference being had to the accompanying drawings, forming part of this specification.

This invention relates to a new and useful improvement in machines for cutting hay and straw, or other articles designed for feed; and

It consists in the construction and arrangement hereinafter described, whereby the cutter or knife is caused to operate in a novel manner, and more efficiently than in other machines of this class.

In the accompanying drawings—

Figure 1 represents a front view of the cutter-lever, knife, and the cutter-box.

Figure 2 is a cross-section of fig. 1, through the line xx .

Similar letters of reference indicate corresponding parts.

A is the face of the cutter-box, against the light projecting flange of which, B, the knife works.

The face is made of cast-iron, with one end, A', extended, so as to support the fulcrum C, of the cutter-lever.

This fulcrum is a pin, which may be either cast in the plate, or secured therein in any suitable manner.

D is the lever, to which the cutting-edge E is attached, by screws or bolts, so that it may be detached, for grinding.

The body of the fulcrum-pin is square in its cross-section.

f is a plate, which is placed on this square part of the pin. It has a round collar, g, over which the lever D fits, and on which it works.

Between the plate f and the face-extension, a number of springs, h, are placed, the tendency of which is to press the plate outward.

i is a thumb-nut, on the end of the fulcrum-pin C.

j is a washer, under the nut and over the plate f.

By this mode of connecting the lever to the extension of the face of the box, the knife E may be much more nicely adjusted to the face B than it could were there no springs to keep it steady.

l represents inclines, formed on the face of the extension A', and upon which the inner face of the outer end or extension d of the lever D works.

These inclines are so arranged, that immediately after the edge E begins its cut, the end d of the lever comes in contact with them at the base; and, consequently, the edge is caused (when completing its stroke) to press, by aid of springs h, more firmly upon the lower rim or flange of the plate A than at any other point in its movement. Thus we completely obviate one of the most objectionable features in the operation of ordinary feed-cutters, viz., the tendency of the cutter to crowd off from the face of the cutter-box, so as to leave the lower portion of the straw-ends uncut.

K represents a curve, in the inner end of the cutting-edge E, and

L is a curve in the lower portion of the face A and flange B.

By the action of the lever, the hay or straw, which is being cut, is forced between these curves before the cut terminates, which completes the cut with less exertion of force than would be required if the feed were forced into an angle, as the curves serve to spread the straw or hay over a broader space.

Having thus described our invention,

We claim as new, and desire to secure in Letters Patent—

1. The combination of inclines l, with a cutter, e, when arranged substantially as and for the purpose set forth.

2. The combination of the inclines l, springs h, pivot-pin C, washer f, with the extension A' and lever D, all constructed and arranged as shown and described.

The above specification of our invention signed by us, this 9th day of November, 1869.

WM. H. ROSSER,
JAMES STIVER.
